VARIABLE-SPEED CODE-TRAINING DEVICES

John H. Hickey, Port Washington, and Louis M. Mitteldorf, Amityville, N. Y., assignors, by direct and mesne assignments, to the United States of America as represented by the Secretary of the Navy

Application July 29, 1952, Serial No. 301,472

6 Claims. (Cl. 178—115)

This invention relates to code-training devices and is directed particularly to a device, controlled by a tape containing punched intelligence, which translates the intelligence into audible signals at a given constant speed while automatically injecting additional adjustable silent periods between each letter, number or word.

The general principle of transmitting code characters at a high rate of speed and injecting additional silent periods for training purposes is not new. In the past, characters were punched on a standard Wheatstone perforator, commonly used in the art, and longer space periods were actually punched into the tape. This method required a separate tape for each effective keying speed.

Another method has been the use of a standard tape having normal space periods with a translating device operative to cause every second, third or fourth character to be dropped, the dropped characters constituting additional space periods. One disadvantage of such a system is that only five or six different keying speeds could be had with a single tape. Another disadvantage is that, because of the omission of characters, readable texts could be transmitted at only one code speed.

Accordingly, it is one object of this invention to provide a code training device using a single punched tape including means for selectively adjusting the injected silent time between characters.

Another object is to provide a training device of the character described utilizing a single control tape and operative to obtain therefrom an infinite number of effective keying speeds, whereby less and less silent time can be injected between characters as the trainee progresses in code-reading proficiency.

A further object of the invention is to provide, in apparatus of the character described, a satisfactory ratio of length of silent periods between letters and words.

Other objects and many of the attendant advantages of this invention will be readily appreciated as the same becomes better understood by reference to the following detailed description when considered in connection with the accompanying drawings wherein:

Fig. 1 is an enlarged view of a section of perforated code tape showing element, character and space relationships,

Fig. 2 is a simplified, perspective diagram of the functional parts of the keying head,

Fig. 3 is a perspective diagram of the tape drive mechanism, and

Fig. 4 is an electrical schematic diagram of the timing control circuit.

In United States Patent No. 1,939,215 issued December 12, 1933, there is shown and described a photoelectric keying head and a perforated tape for use in an automatic code training device. The present invention constitutes an improvement thereover, and therefore, only so much of a keying head and tape such as is disclosed in said patent is described herein as is deemed adequate to afford a complete disclosure of the present invention.

Fig. 1 of the drawings illustrates the code tape on

2

which a message is punched, as by means of a standard Wheatstone perforator. The small center holes 10 engage the teeth of a star wheel 12 (see Figs. 2 and 3), which rotates to pull the tape through the keying head, indicated generally by the number 14. As the tape is drawn through the keying head, light from an exciter lamp 16 passes through the larger holes 18, above the center of the tape and excites a "tone-on" photo-tube 20 to provide a "tone-on" electrical impulse. In a similar manner, light from an exciter lamp 22 passes through the lower holes 24 in the tape to excite a photo-tube 26 which produces a "tone-off" electrical impulse.

Two pairs of focusing lenses 28, 34 and 32, 30 are provided in the keying head 14 to concentrate light from the exciter lamps 16 and 22 into two bright beams, one falling on each of a pair of laterally displaced slits 36, 38 in a tape retaining plate 40 along which the tape is drawn. These lenses focus the light that passes through the holes 18, 24 in the tape, through the slits 36, 38 in the tape retaining plate 40, and through holes in a rotating cylindrical shutter 42, onto the photo-tubes 20, 26. The shutter 42 is provided with a set of six "tone-on" holes 44, and six "tone-off" holes 46. These holes are staggered evenly so that, as the shutter 42 revolves, first an "on" hole 44 comes beneath the center of the "on" aperture slit 36, and then an "off" hole comes beneath the center of the "off" aperture slit 38. Consequently, light from both "on" and "off" holes 44 and 46 does not pass through and reach the photo-tubes 20, 26 at the same time, but alternates, and then only in pulses. Fig. 2 shows the beam of light from the exciter lamp 16 reaching the "tone-on" photo-tube 20.

In automatic code transmission, the dots, dashes and spaces occupy a definite length of tape, as shown in Fig. 1. A dot or a dash is called an element. Transmission of either a dot or a dash includes the time during which the audible tone is on and also a portion of time in which the tone is off. On the code tape, a dot occupies the distance between two center drive holes 10. This distance is further divided into two smaller equal units called bauds. For transmission of a dot, the first baud of tape travel is the "tone on" time, while the second baud is the "tone off" time. The dash, when transmitted, has three bauds of "tone on" time, and one baud of "tone-off" time as indicated. In the drawing, shaded sections indicate "tone-on" time, and unshaded sections indicate "tone-off" time.

A character is the combination of dots and dashes that constitutes a letter, number, punctuation mark, or other symbol.

A spacing unit is the period of silent time between characters and words. It is separate from that baud of space associated with the elements. As indicated in Fig. 1, the single unit of space between letters occupies two bauds of tape travel; the triple unit of space between words requires six bauds of tape travel.

The tape drive mechanism (see Fig. 3), comprises an electric motor 46 having an output shaft 48 coupled through a flexible coupling member 50 to the driving clutch member 52 of a clutch assembly indicated generally by the number 54. Cooperatively disposed with respect to the driving clutch member 52 is a moving clutch member 56 supported on the shutter drive shaft 58 which is journaled in a bracket 60. The facing ends of the driving clutch member 52 and the moving clutch member 56 have saw-tooth serrations, as indicated by the numbers 53 and 55, respectively. The moving clutch member 56 is longitudinally slidable on its shaft 58, but not rotatable with respect thereto, by virtue of an ordinary longitudinal key and keyway interconnection, not shown. Rotatably disposed in an annular

groove in the moving clutch member 56 is a collar 62 having a pair of opposed flat surfaces 64 within which are located the ends of a pair of armature arms 66, 68 of a control relay 70. The relay 70 is normally held at open position by action of a spring 72, whereby the moving clutch member 56 is held retracted from engagement with the driving clutch member 52. When the relay 70 is energized, by a circuit hereinbelow described, the armature arms 66, 68 are drawn in, carrying with them the moving clutch member 56 to bring it into engagement with the driving clutch member 52. Gear mechanism 73 operatively interconnects the shutter drive shaft with the star wheel 12 so that they always rotate at proper relative speeds to produce the "tone on" and "tone off" impulses in accordance with the intelligence perforated on the tape. The speed of the motor 46, and the lateral spacing of perforations on the tape are such that when the clutch assembly 54 is in engagement, code is transmitted at a speed of about twenty words per minute.

Additional time or space periods between characters and words is inserted at lower rates of code transmission by intermittent deenergization of the control relay 70, as hereinbelow described.

A toothed clutch stop member 74 fixed to the bracket 60 is provided to engage the toothed outer portion of the moving clutch member 56 in order to prevent "coasting" or uncontrolled motion of the tape while the clutch is disengaged position.

The photo-tubes 20, 26 are electrically connected, in a manner known in the art and therefore not detailed herein, so that the "tone-on" photo-tube 20 produces a negative voltage pulse and the "tone-off" photo-tube produces a positive voltage pulse. Thus, the output voltage curve of the photo-tube circuit, when transmitting the first character "A" of the portion of tape shown in Fig. 1, will appear as a train of voltage pulses as indicated by the number 78 of Fig. 4. This voltage pulse train is fed through an amplifier 80 into a locking circuit 82 operative to produce positive output voltage pulses of substantially square wave-form of width equal to the distance between the "tone-on" and "tone-off" pulses. The output wave-form of the locking circuit is indicated by the reference number 84. Such locking circuits are commonly known in the electronics art and therefore not further described herein. The square-wave pulse train acts as a gate to control the output of a tone generator 86, such as by unbiasing a vacuum tube normally biased to cut-off, which vacuum tube controls the output audio-frequency voltage of the tone generator to a loud speaker 87. Such gate control circuits are also well known in the electronics art and therefore not described herein in detail.

A timing-control circuit, indicated generally by the number 89, regulates the tape movement through the keying head 14 by intermittently energizing the control relay 70. This circuit is actuated by the pulse-train output voltage of the locking circuit 82, indicated by the reference number 88. It is to be noted that the output voltage of the locking circuit 82 which is the input voltage to timing-control circuit, is in phase with respect to the input voltage to the amplifier from the keying head photo-tubes.

In the embodiment of this invention, the timing-control circuit 89 is inoperative at 20 words per minute (W. P. M.) because control relay 70 is continuously energized by grounding the grid of pentode or control relay tube 94. Moving clutch member 56 is held against the teeth of driving clutch member 52 and star wheel 12 rotates, drawing the tape through the keying head at the constant rate of 0.8 inch per second.

At variable code speeds between 4 to 19 W. P. M. the tape, when it travels, moves at 0.8 inch per second. To reduce the W. P. M. rate, the motion of the tape is stopped between characters, words and spacing units.

The tape is halted by the time control circuit 89 which de-energizes control relay 70 at the proper intervals and for the proper time. Coil 70, when de-energized, permits moving clutch member 56 to snap back against clutch stop member 74, as described hereinbefore, instantly stopping rotation of star wheel 12 and tape travel.

A negative voltage (during "tone-on" time) from the amplifier 80 is taken from the center arm of the potentiometer R₁ and applied to the cathode of one section of a double-diode 90 as shown in Fig. 4. Since the plate of this diode is connected to ground through the variable resistor R₂, the plate becomes positive with respect to the negative cathode. Current flows from cathode to plate of duo-diode 90 and down to ground through resistor L₂ developing a negative voltage on the grid of a triode 92. This voltage is greater than the cut-off value of triode 92 and, consequently the tube is blocked, or non-conducting. When triode 92 is non-conducting, the voltage at the common junction of the voltage divider resistors R₄ and R₅ in the plate circuit of the triode becomes positive. Since the voltage at this junction point is connected to the grid of the clutch-control pentode 94, the pentode conducts, energizing the clutch-control relay energization coil 96 in its plate circuit, and the tape moves through keying head 14.

A "tone-off" voltage pulse from potentiometer R₁ causes the cathode of the first section of the double-diode 90 to become positive with respect to its plate, and the tube ceases to conduct. Although the tone is now off, the tape travel continues because the negative voltage applied across the variable resistor R₂ has charged the condenser C₁ connected in parallel therewith. This negative voltage, applied to the grid of the triode 92, holds that tube at cut-off until the condenser charge leaks off and falls below the cut-off value of the tube; it then conducts, switching the voltage to the grid of the pentode 94 from positive to negative. This cuts off relay-control pentode 94, de-energizes the clutch coil 96, and halts tape travel.

The triode 92 has a fixed cut-off value, consequently, the greater the negative voltage applied across the resistor R₂ during "tone-on" time, the longer time will be required for that voltage to fall to the conduction point after the tone goes off. Adjustment of the potentiometer R₁ varies this applied voltage. The potentiometer is set at that point which applies a voltage sufficient to hold the relay coil 96 energized until the tape has traveled the distance of one baud after the element "tone-on" time. When the baud of tape travel has passed, the clutch coil 96 becomes de-energized and tape travel stops for a period of dead time unless, of course, the "tone-on" pulse of a following dot or dash keeps the relay coil energized.

When the tape stops, it will not travel again until the clutch coil 96 is re-energized, or until triode 92 is cut off by a negative voltage pulse generated by a relaxation oscillator portion of the timing control circuit 89 hereinbelow described, which drives the grid of the triode 92 to cut-off. This negative voltage, indicated by the number 98, is applied to the second or lower cathode of the double diode 90, producing current flow from said plate to its cathode, through variable resistor R₂ and ground, developing a greater than cut-off voltage at the grid of the triode 92.

The function of the negative relaxation oscillator voltage 98 developed across the variable resistor R₂ is to hold the triode 92 cut off and thus energize the clutch coil 96 for the period of time required to move the tape forward one spacing unit of two bauds. This voltage is a sharp saw-tooth pulse. Its shape is not important, however, because the proper period of voltage decay time is controlled by adjustment of the variable resistor R₂. This adjustment changes the RC time constant of

parallel-connected variable resistor R₂ and condenser C₁, and, consequently, the time required for the sharp voltage pulse 98 from the relaxation oscillator to leak off to ground. When this voltage reaches the cut-off value of the triode 92, that tube conducts and de-energizes the clutch coil 96, as hereinabove explained, thus stopping the tape after one unit of space travel.

When the tape stops for dead time between words, a single pulse from the relaxation oscillator moves the tape forward one spacing unit of two bauds. At this point the triode 92 conducts again and the tape travel stops, inserting a second period of dead time. At the end of the third spacing unit between words, the "tone-on" pulse energizes the clutch and the tape travels on into transmission of the next character.

The relaxation oscillator is a two-tube "flip-flop" RC oscillator comprising triodes 100 and 102. This type of oscillator operates as an over-biased multivibrator which has a stable state in which the oscillator remains, unless disturbed by a sudden input voltage of proper polarity. Application of a triggering voltage causes the oscillator to go through an unstable state and then return to the stable state, in which it remains until another triggering pulse or voltage is applied. It is the unstable state that supplies the sharp pulse 98 of negative voltage to the second or lower cathode of double diode 90.

Normally, the triode 100 is cut off when the clutch is engaged, and therefore the oscillator is inoperative. When the clutch is disengaged after the baud unit at the end of a letter, or between spacing units, the triode 100 is triggered by applying the positive voltage which appears at the common junction of the voltage divider resistors R₇, R₈ in the plate circuit of triode 104.

A cycle of operation will be traced, starting with the relaxation oscillator inoperative, that is, with the triode 100 cut off, as during a "tone-on" period. Under this condition, the triode 100 draws no current through its plate load resistor R₉, but the grid of triode 102, which is connected to that plate, draws current through resistor R₉, reducing the voltage at the grid to about +150 volts. The cathode potential of triode 102 is about the same voltage. During the "tone-on" portion, triode 102 conducts, but a high resistance R₁₁ in the cathode circuit limits the plate current flow in the tube to a very low value, and triode 102 acts as a high resistance to ground. Consequently, the voltage at the common junction point of the voltage divider resistors R₁₂, R₁₃ in the plate circuit of triode 102 becomes approximately +50 volts with respect to ground.

One side of the capacitor C₃ is connected to the +290 volt supply and the other side to the cathode of triode 102. Since the cathode is at +150 volts, capacitor C₃ becomes charged to the difference potential of 140 volts. When the clutch is de-energized, a positive voltage is applied to the grid of triode 100 allowing it to conduct. When triode 100 conducts, the voltage at the grid of triode 102, which is connected to the plate of triode 100, drops to about +30 volts.

Triode 102 is then cut off; and its cathode voltage, due to plate-current flow through resistor R₁₁, vanishes. However, capacitor C₃, which has been charged to 140 volts, now has 290 volts applied across it, and new charging current flows up through cathode resistor R₁₁, holding the cathode at a positive value sufficient to keep the triode 102 cut off. As the voltage across capacitor C₃ rises, both the charging current through R₁₁, and the voltage at the cathode decrease until the cathode potential reaches the conduction value of the tube.

When the triode 102 starts to conduct, plate current flows through the resistor R₁₁, and the cathode voltage, due to plate current, rises an additional +30 volts. The voltage across the capacitor C₃, plus that across the resistor R₁₁ is now greater than the 290 volt supply, and the capacitor discharges back down resistor R₁₁. At this

instant the plate-current flow up through resistor R₁₁ is cancelled by the capacitor current down and the potential difference across resistor R₁₁ drops to zero. In effect, this grounds the cathode, maximum current flows through the triode 102, and the tube acts as a shorting switch across the voltage-divider circuit comprising the resistors R₁₂ and R₁₃, driving the voltage at their mutual junction point sharply negative. At the same time, the sharp voltage drop at the plate of triode 102 is passed back through the coupling capacitor C₂ to the grid of the triode 100, cutting off that tube.

The negative pulse at the junction of resistor R₄ and R₅ is applied to the second lower cathode of the double-diode 90. Current flows up through R₂, triode 92 is cut off, the clutch coil 96 is energized, the triode 104 conducts, and a negative voltage appearing at the junction of voltage divider resistors R₇ and R₈ in the plate circuit of triode 104, holds the triode 100 cut off. Thus, the relaxation oscillator is held in the "off" state until the voltage at the grid of triode 100, connected at the junction point of the divider resistors R₇ and R₈, again goes positive.

During spacing intervals occurring at the end of a letter, word, or spaces between them, there are no holes in the tape. Since no pulse of light can reach the phototubes to energize the amplifier 80, the charge on the capacitor C₁, due to the negative pulse from the relaxation oscillator, leaks off. At the instant that the voltage across the capacitor C₁ drops to the conduction point of the triode 92, the pentode 94 and the triode 104 are cut off and the voltage at the grid of triode 100 becomes positive; triode 100 is then turned "on" and the cycle starts again.

Adjustment of variable resistor R₂ determines how long the triode 92 remains cut off, how long the clutch coil 96 is energized, and, consequently, how much tape travels through the keying head 14 during this spacing period. The variable resistor R₂ is adjusted to permit a minimum of two bauds of tape to travel during a spacing unit.

After the clutch is de-energized, the value of the variable resistor R₁₁ determines how long the capacitor C₃ will take to charge up and how long before the voltage across the resistor R₁₁ falls to conduction value of the triode 102. During this period of charging, the tape is motionless. Consequently, adjustment of the variable resistor R₁₁ controls the amount of dead time between letters and words. By proper selection of circuit element values, effective keying speeds of from about four to twenty words per minute can be attained with a single tape by adjustment of the variable resistor R₁₁.

The following values of circuit elements comprising the timing control circuit have been found to be satisfactory in a practical embodiment of the invention:

55	C ₁	-----	mfd	.05
56	C ₂	-----	mfd	.25
57	C ₃	-----	mfd	1
58	R ₂	-----	megohm	1
59	R ₃	-----	ohms	47,000
60	R ₄	-----	do	100,000
61	R ₅	-----	do	150,000
62	R ₆	-----	do	33,000
63	R ₇	-----	do	100,000
64	R ₈	-----	do	150,000
65	R ₉	-----	do	33,000
66	R ₁₀	-----	do	33,000
67	R ₁₁	-----	megohms	2.5
68	R ₁₂	-----	ohms	100,000
69	R ₁₃	-----	do	150,000
70	Relay coil 96	-----	do	11,000

Obviously, many modifications and variations of the present invention are possible in the light of the above teachings. It is therefore to be understood that within the scope of the appended claims the invention can be

practiced otherwise than as specifically described. What is claimed is:

1. Training apparatus, comprising a movable tape having spaced indicia corresponding to intelligence; means translating said indicia into signals and translating the latter in a form receivable by a trainee for identification; said translating means comprising a drive wheel adapted to advance said movable tape, a drive motor, and a clutch member between said drive wheel and said drive motor, said clutch member being operable selectively to engage or disengage said drive motor relative to said drive wheel; and means responsive to the occurrence of a space between adjacent indicia of said tape for actuating said clutch member to disengage said drive motor for a predetermined length of time, and to engage it again at the end of said predetermined length of time.

2. The apparatus as in claim 1 further comprising means for controlling the duration of said predetermined time, whereby the word rate of transmission of the intelligence to the trainee can be controlled.

3. The apparatus as in claim 1 wherein said clutch member actuating means comprises a timing circuit comprising an R-C network adapted to be charged during the interval that indicia are translated, and discharged during the interval between adjacent indicia.

4. The apparatus as in claim 1 wherein said clutch member actuating means comprises a generator for providing a pulsed signal of adjustable pulse-repetition frequency, individual pulses thereof being operable to initiate actuation of said clutch member into engagement after a lapse of a predetermined time interval.

5. Training apparatus comprising a movable tape record having thereon spaced indicia corresponding to intelligence, means translating said indicia into signals and

transmitting the latter in a form receivable by a trainee for identification, means responsive to the occurrence of a space between adjacent indicia for interrupting the movement of said record for a predetermined time, said interrupting means comprising a timing circuit comprising an R-C network adapted to be charged during the interval that indicia are translated and discharged during the interval between adjacent indicia, and means operable to initiate the movement of said record at the end of said predetermined time.

6. Training apparatus comprising a movable tape record having thereon spaced perforations corresponding to intelligence, said perforations including tone-off and tone-on perforations means translating said perforations into signals and transmitting the latter in a form receivable by a trainee for identification, means responsive to the occurrence of a space between a tone-off and a tone-on perforation for interrupting the movement of said record for a predetermined time, said interrupting means comprising a timing circuit comprising an R-C network adapted to be charged during the interval that perforations are translated and discharged during the interval between tone-off and tone-on perforations, and means operable to initiate the movement of said record at the end of said predetermined time.
